UNITED STATES PATENT OFFICE.

SYLVESTER L. JOINER, OF McGREGOR, TEXAS.

CAR-COUPLER-LOCK-LIFTER SAFETY ATTACHMENT.

Application filed July 28, 1927. Serial No. 209,078.

The invention relates to a car coupler lock lifter safety attachment.

It has been found by experience with the American Railway Association D coupler 5 that the shoulder provided at the rear edge of the lower end of the lock lifter to prevent the lock lifter from dropping too far in time becomes worn and that the lock lifter when worn drops into the coupler head a sufficient distance to cause the worn shoulder 10 to catch on the interior wall of the draw head and prevent upward movement of the lock lifter and the unlocking of the coupler head. When this takes place loss of time, 15 inconvenience and frequently damage to the car coupler results before the coupler can be unlocked or disconnected from the coupler head of the car to which it is coupled.

The object of the present invention is to 20 provide a simple, practical, and efficient safety attachment for lock lifters of the said type of coupling adapted when applied to a lock lifter to move freely in its locking and unlocking movements and capable of effectually limiting the downward movement 25 of the lock lifter after the latter becomes worn in use and of supporting a worn lock lifter in proper operative position without liability of being accidentally lifted by the 30 inward and outward movement of the coupler head.

A further object of the invention is to 35 provide a car coupler lock lifter safety attachment of this character adapted to fit closely the top of the coupler head and capable of forming a partial cap to cover the opening for the lock lifter and of excluding much of the dust, dirt, snow, ice and the like which would otherwise enter the said opening and affect the lubricant which is usually 40 supplied to the interior of the couplings and cause increased wear of the parts.

Another object of the invention is to provide a car coupler lock lifter safety attachment 45 which may be readily applied to car couplers on cars in use, without necessitating the removal of the releasing mechanism for operating the lock lifter.

Another object of the invention is to provide 50 a simpler form of the lock lifter attachment designed to be applied to lock lifters either when the releasing or operating mechanism is disconnected or before the same is applied to the lock lifter.

With these and other objects in view, the 55 invention consists in the construction and

novel combination and arrangement of parts hereinafter described, illustrated in the accompanying drawings, and set forth in the claims hereto appended, it being understood 60 that various changes in the form, size, and minor details of construction, within the scope of the claims, may be resorted to without departing from the spirit of the invention or sacrificing any of the advantages 65 thereof.

In the drawings:

Figure 1 is a longitudinal sectional view of a car coupler of the D type provided with a lock lifter safety attachment constructed 70 in accordance with this invention.

Fig. 2 is a similar view of a D coupler showing the manner in which a worn lifter drops below its normal position.

Fig. 3 is a plan view of the lifter attachment, partly in section.

Fig. 4 is a front end view of the same.

Fig. 5 is a plan view of a simpler form of the invention.

Fig. 6 is a transverse sectional view of 80 the same.

In the accompanying drawings, in which are illustrated the preferred embodiments of the invention, 1 designates a car coupler lock lifter attachment arranged upon the top of a D coupler 2 and provided with a tapered opening 3 receiving and conforming to the cross sectional configuration of the lock lifter 4 of the said coupler. The coupler illustrated in the accompanying drawings is the 85 American Railway Association D coupler, such as is illustrated in Patent No. 1,542,303, dated June 16, 1905. The opening 3 tapers forwardly and the front end wall is curved and the rear end of the said opening 3 is normally closed by a transverse bolt 5 provided at one end with a head 6 and secured in aligned openings 7 of the rear ends of the sides of the safety attachment by a cotter pin 8 which is passed through 90 a perforation 9 in the bolt 5, but any other suitable fastening means may, of course, be employed, as will be readily understood, and a rotary sleeve 10 is mounted on the bolt 5 between the sides of the lifter attachment 105 to prevent binding of the lock lifter against the bolt and wear of either of the parts.

The lock lifter attachment rests upon the top of the D coupler and is curved in cross section to present a concave lower face 11 110 to fit tightly against and conform to the configuration of the convex upper face or

crown of the top of the D coupler. The lock lifter attachment is of a thickness to receive and support the uncoupling lever or release rigging 12 before the lock lifter wears sufficiently to permit the shoulder 13 of the lock lifter to pass beneath the short lock down lock 14 of the car coupler. The thickness of the lock lifter safety attachment may be varied to limit the amount of wear of the shoulder 13 before the wear of the shoulder causes the uncoupling lever or release rigging 12 to rest upon the lock lifter attachment. When the lock lifter attachment is first applied to the coupler, it is preferable to have the releasing lever or uncoupling rigging spaced from the lock lifter attachment to permit a lifting out of the car coupler before the wear of the parts is sufficient to cause the uncoupling lever or release rigging 12 to rest upon the lock lifter attachment, but it will be readily apparent that the thickness may be increased to the extent of causing the uncoupling lever or release rigging 12 to rest upon the device 25 and prevent any increased downward movement of the lock lifter through wear of the shoulder 13.

In the form of the invention illustrated in Figs. 1 to 4, inclusive, of the drawings, in which the removable bolt 5 is employed, the devices may be readily attached to cars in use without removing any of the release rigging.

In the form of the invention illustrated in Figs. 5 and 6 of the drawings, a simpler form of the device is shown. In this form of the invention, the device consists of a plate or member 15 provided with a tapered opening 16 which is closed at both ends by integral portions of the plate or member. This form of the lock lifter attachment is curved in cross section to present a lower curved face 17 to the convex upper face or crown of the car coupler, and the said device is applied to the lock lifter when the uncoupling or release rigging is removed from the lock lifter. Also, this form of the device might be applied to the lock lifters of car couplers before the uncoupling lever or release rigging is assembled. The lock lifter attachments are designed to be constructed of drop forged steel, malleable iron, or other strong material, and they are capable of a limited sliding movement on the 50 coupler head without any tendency to raise the lock lifter and they do not in any manner interfere with the movement of the lock

lifter. As the construction and operation of the D coupler of the American Railway Association is well understood, and is described in the aforesaid patent, a specific description of the same is deemed unnecessary.

What is claimed is:

1. A lock lifter attachment for car couplers comprising a member having an opening to receive and permit free independent movement of the lock lifter of a car coupler, said member being adapted to rest upon the top of the coupler head and arranged to receive and support the release rigging to limit the downward movement of the lock lifter. 60

2. A lock lifter attachment for car couplers comprising a member having an opening to receive and permit free independent movement of the lock lifter of a car coupler, said member being adapted to rest upon the top of the coupler head and arranged to receive and support the release rigging to 70 limit the downward movement of the lock lifter, and being curved to present a concave lower face to the coupler face and forming a proper support for the lock lifter opening 80 of the coupler head. 85

3. A lock lifter attachment for car couplers comprising a lock lifter attachment member having an opening to receive the lock lifter and permit free independent movement thereof, said opening extending 90 to the rear end of the attachment member to permit the attachment to be applied to the lock lifter without removing the release rigging, and a removable transverse locking device extending across the said opening 95 and confining the attachment on the lock lifter.

4. A lock lifter attachment for car couplers comprising a lock lifter attachment member having an opening to receive the lock lifter and permit free independent movement thereof, said opening extending 100 to the rear end of the attachment member to permit the attachment to be applied to the lock lifter without removing the release rigging, and a removable transverse locking device extending across the said opening 105 and confining the attachment on the lock lifter, the attachment member being curved to present a concave lower face to the upper 110 face of the coupler.

In testimony whereof I have hereunto set my hand.

SYLVESTER L. JOINER.
